UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

METALLIC-DOOR STRUCTURE

Application filed July 31, 1920. Serial No. 400,399.

To all whom it may concern:

Be it known that I, JOSEPH LEDWINKA, residing at 25th Street and Huntington Park Avenue, Philadelphia, Pennsylvania, have invented certain new and useful Improvements in Metallic-Door Structures, of which I declare the following to be a full, clear, and exact description.

My invention relates to improvements in metallic door structures. My invention relates particularly to the construction of metallic doors for motor vehicles, and to the means for mounting a curtain rod socket in such doors, and also the means for mounting the hinges and reinforcing the door adjacent the hinges.

One of the objects of my invention is to provide means for mounting a curtain rod socket in an all-metal door. Another object of my invention is to provide novel and efficient means for mounting the hinges on the door and for stiffening and reinforcing the door adjacent the hinges.

Further objects, and objects relating to economies of material and details of construction, will definitely appear from the detailed description to follow. I accomplish the objects of my invention by the devices and means set forth in the following specification. My invention is clearly defined and pointed out in the appended claims.

A structure, constituting a preferred embodiment of my invention, is illustrated in the accompanying drawings, forming a part of this specification, in which:

Fig. I is a view in side elevation of a door constructed in accordance with my invention.

Fig. II is a top plan view of the door, a portion being broken away to show certain features of the construction.

Fig. III is a detail, sectional view, taken substantially on the line III—III of Fig. I.

Fig. IV is a detail, sectional view, taken substantially on the line IV—IV of Fig. III.

Fig. V is a fragmentary view in side elevation, taken substantially on the line V—V of Fig. IV.

Fig. VI is a detail perspective view of one member of the curtain rod socket holder.

Fig. VII is a perspective view of the other member of the holder.

Fig. VIII is a view in side elevation of the curtain rod socket.

Fig. IX is a detail, sectional view through a portion of the door at one end near one of the hinges, the hinge being shown in full lines.

Fig. X is a detail, sectional view taken substantially on the line X—X of Fig. IX.

In the drawings, similar reference numerals refer to similar parts throughout the several views, and the sectional views are taken looking in the direction of the little arrows at the ends of the section lines.

In many types of automobiles, it is customary to provide, in the upper portion of the door, a socket which is to receive an upright curtain rod, so that the side curtain above the door will move with the door, as it is opened. This curtain arrangement is becoming standard practise on many of the recent models with the result that it has been necessary to provide a socket in the door to receive this curtain rod. The curtain rod is, as a rule, inclined upwardly at a slight angle, so that its upper end will lie outside the edge of the top. This requires that the curtain rod socket be disposed in the door at a slight angle to the general plane of the door.

In the construction of motor vehicle doors in which the metal panel is mounted on a wooden frame, it was a comparatively easy matter to bore a hole in the frame at the required angle and to insert the socket in such hole. In all-metal doors, however, we have no such frames and it has been necessary to devise means for mounting the socket in the chamber formed between the inner and outer panels of the door.

It is among the special purposes of my present invention to provide a mounting for the curtain rod support in an all metal door which is simple in structure, economical to manufacture, easy to apply in the construction of the door, and efficient in operation, and which mounting is composed of suitable sheet metal stampings so formed or shaped as to support the curtain rod in the desired position of vertical inclination, and

in carrying out the objects and purposes of my invention I propose to mount the curtain rod support in the chamber or space between the sheet metal panels of the door structure. The curtain rod support may be constructed in many different ways and mounted or supported within the space or chamber between the door panels in various ways. I have shown one structure of support composed of sheet metal stampings which is simple and efficient, and I have shown one arrangement for mounting the same which has proved satisfactory, but my invention in its broadest scope is not to be limited or restricted in respect to the details of structure of the support or holder, nor in respect to the details of mounting of the support or holder.

In constructing the holder, in accordance with my invention, and in one form of embodiment thereof, I employ two metal stampings so formed that when they are assembled together they constitute a holder to receive and support a socket member in which the curtain rod is received, the socket member being maintained at the desired vertical angle.

The curtain rod is supported at its lower end in a socket member shown in detail in Fig. VIII, and comprises a rectangular shaped lower portion 38 having openings through one of the side walls thereof as indicated at 39. The upper portion 40 of the socket member is shown in this instance as cylindrical in form, and when in use the lower end of the curtain rod is slipped into this socket member. The mounting for the socket member in accordance with my invention is composed of the metal stampings, one form of which is shown respectively in Figs. VI and VII. The stamping shown in Fig. VI designated generally by reference numeral 24, is shaped to form the walls 28 and 27 in angular relation with respect to each other, the wall 28 being vertically inclined so as to maintain the socket member above referred to in the desired angle of vertical inclination. The other stamping of the holder is formed with the walls or portions 33, 34, in angular relation with respect to each other. When the two stampings composing the holder are assembled and suitably secured together they cooperate to form a space between them which conforms to the cross-sectional outline of the shank portion 38 of the socket member to receive said socket member therein, and hold the same in proper position and inclination to receive and support the curtain rod. The two stampings composing the holder may be secured together in assembled relation in any suitable or convenient manner. A simple arrangement is shown wherein one edge of one of the

stampings is formed with a flange 36 to be received and to rest against the portion 27 of the stamping 24, and to be secured thereto by spot welding or otherwise. The opposite edge of said first mentioned stamping, in the form shown, is provided with tongues 37, arranged to be inserted through openings 29 in the portion or wall 28 of stamping 24, and to be clinched over against the outer surface of said portion 28, as clearly shown in Fig. III, thereby efficiently securing the two stampings together. Of course the stampings may be secured together in many other different ways.

The holder constructed in its essential features, as above described, may be mounted within the space between the door panels in any suitable or convenient manner. In the drawings I have shown an all metal door structure, including the outer and inner panels 10, 12. In constructing the door these panels are suitably formed and connected together to afford a space or chamber therebetween. The holder for the socket member above described is mounted, in accordance with my invention, in any suitable or convenient manner within this space or chamber. In the particular form shown, to which, however, my invention is not to be limited or restricted, I mount the socket holder upon the inner panel 12 of the door, and for this purpose one edge of the stamping 24 is flanged as at 25 to be received against the inner wall or surface of the panel 12, and to be secured thereto by riveting or otherwise as indicated at 26. The other edge portion 30 of the stamping 24 is shown as received against a shoulder portion 41 formed in the edge of the door panel 12, and is secured thereto by rivets or otherwise as indicated at 32.

As above indicated, the panels 10, 12 may be joined together at their edges in offset relation with respect to each other in any suitable or convenient manner. One arrangement is shown wherein the edge of the outer panel 10 is formed with a bead 11 and is flanged over the edge 15 of the inner panel 12, as indicated at 16. Any suitable means may be provided for fastening the socket member when seated within the socket or mounting above described. A simple arrangement is shown wherein one of the stampings composing the holder is formed with lugs or projections 35 adapted to snap or spring into the holes 39 of the socket member when the latter is forced home into the support, the resiliency of the parts permitting this action to be accomplished. The upper edges of the door panels likewise may be connected together in any suitable or convenient manner. It is customary to form the outer panel 10 with an inturned flange 17 at its upper edge to form the molding or

upper edge portion of the door, and the upper extremities of the door panels 10, 12 are brought together and fastened by spot welding or otherwise. It is customary to so stamp or shape the panels at the upper edge of the door to form a channel indicated at 22 by outwardly bent portions indicated at 18 and 21 respectively. A tacking strip, not shown, for the lining or upholstery for the inner surface of the door to be secured thereto is provided. The bead 17 and the flange portions 18, 21 of the door panels are of course perforated or formed with openings to receive the upper portion 40 of the socket member therethrough, and to permit the curtain rod to be inserted into the socket member through an opening in the rail or bead portion 17.

From the foregoing description it will be seen that I provide an exceedingly simple and effective socket holder structure or mounting for an all metal door wherein such mounting is disposed wholly within the space or chamber between the panels composing the door and is supported in such disposition, and wherein the socket member is received and fastened in the holder, all of the parts of said holder being concealed within said space or chamber.

If desired, the door, as usual, may be equipped with the usual door latch or bolt indicated generally at 23, and also the inner panel 12, if desired, may be stamped out as indicated at 13 to form the usual door pocket or receptacle. These features, however, are not essential to my present invention.

It has heretofore been a common practice of the art to attach the hinge straps of metallic door structures to one or the other of the sheet metal panels composing the door, and to cut openings through the edge flanges of the panel to permit the hinge strap to extend outwardly therethrough. This practice is objectionable for the reason that when the doors are subjected to the rough usage of slamming and resulting shock and jar, the danger is incurred of marring or distorting the door panel to the surface of which the hinge straps are secured, and, in addition, by cutting openings in the edge flange of the door panel through which the hinge straps project the panel is weakened and at a point where it requires strength and rigidity in order to enable the door structure to withstand the shocks and jars incident to slamming of the doors. It is among the special purposes of my present invention to provide a mounting for the hinge straps for sheet metal automobile doors which avoids these and other objections, and in accordance with my invention I propose to employ a reinforcing stamping or member to which the hinge straps are secured, and to apply such reinforcing

stamping or member to one of the door panels, thereby enabling the shocks and jars of the door to be taken by the auxiliary reinforcing plate or stamping and relieving the door panel itself of the resulting strains.

I propose to employ the auxiliary stamping upon which the hinge straps are mounted to reinforce the edge flange of the door panel to which the stamping strap carrying the hinge straps is secured at the points where such edge flange is weakened by the holes or openings formed therein for the hinge straps to pass through. Many specifically different structures may be employed to embody the features above described. I have shown one arrangement wherein a reinforcing stamping indicated at 45 is secured by spot welding or otherwise as indicated at 46, see Fig. X, to the inner surface of the inner door panel 12 adjacent its hinge edge. At the points where the hinge straps are to be secured portions 49 of the reinforcing plate are pressed outwardly so as to accommodate the shank portions or butts 44 of the hinge straps 42 between such pressed out portions of the reinforcing plate and the inner surface of the panel 12. The shanks or butts 44 are fastened or secured to the pressed out portions 49 of the reinforcing

plate by bolts, rivets or otherwise, as indicated at 54. The reinforcing plate, as indicated in Fig. I, extends for the larger portion of the vertical dimension of the door panel 12 and is secured to the inner surface of said panel at various points throughout its bearing thereagainst, thus distributing any strains which may be imparted to the panel through its hinge supports, and since the hinge butts or shanks are supported upon and secured to the pressed out portions of the reinforcing stamping or plate the door panel itself is largely relieved of the strains, and hence marring or distortion of the door panel is reduced, if not prevented.

The outer edge of the reinforcing plate 45 is flanged as indicated at 47, and lies against and is secured to the flange 14 of the door panel. Both the door panel flange and the flange of the reinforcing plate are formed with openings indicated at 41 and 48 through which the shank or butt portions of the hinge straps 42 extend, but the reinforcement of the door panel flange afforded by the flange of the reinforcing plate strengthens the door panel flange where it would otherwise be weakened by the holes or openings formed therein. Thus it will be seen that the reinforcing plate or stamping serves the double purpose of a support for the hinge straps and also of a reinforcement for the edge flange of the door panel.

Thus it will be understood that many changes in details will readily occur to persons skilled in the art and still fall within the spirit and scope of my invention.

Having thus described my invention, what I claim as new and desire to secure by Letters Patent is:

1. In a metallic door structure, the combination of inner and outer panels having their edges secured together and their body portions offset to form a chamber therebetween, a socket holder including a stamping, having two walls extending at right angles to each other, one of said walls being perpendicular to the inner panel, and the other of said walls being inclined at an angle to said inner panel, means for fastening said stamping to said inner panel, a member clamped to said stamping and having two portions at right angles to each other, forming with said stamping, a rectangular holder having its axis inclined at an angle to the inner panel and a socket mounted in said holder.
2. In a metallic door structure, the combination of inner and outer door panels having their edges secured together and their body portions offset to form a chamber therebetween, a member fastened to the inner panel and having two wall portions at right angles to each other, a member mounted on said first-named member and having wall portions at right angles to each other and to the corresponding portions of said first named member, said members together forming a socket holder, and a socket mounted in said holder.
3. In a metallic door structure, the combination with inner and outer panels having their edges secured together and their body portions offset to form a chamber therebetween, of a holder member mounted on the inner panel, and disposed within said chamber, said member having slots therein, and a keeper member having tongues disposed in said slots and bent over to secure said members together, a curtain rod socket disposed within said chamber and keeper members co-operating to form a support within said chamber for the said curtain rod socket.
4. In a metallic door structure, the combination with inner and outer panels having their edges secured together and their body portions offset to form a chamber therebetween, of a socket holder having a struck up portion projecting inwardly from the wall thereof, a curtain rod socket mounted in said holder, and provided with an opening to receive said struck up portion, and means to support said socket holder upon the inner panel of the door and within said chamber.
5. In a metallic door structure, the combination with an inner and outer sheet metal panels having their edges secured together and their body portions offset to form a chamber therebetween, one of said panels having a flange at its upper edge to form a moulding for the upper edge of the door, said flange having an opening therethrough, of a holder disposed within said chamber in line with said opening, and a curtain rod socket insertable through said opening and into said holder, and means carried by said holder and engaging said socket to retain the same when in place in said holder.
6. In a metallic door structure, in combination with inner and outer sheet metal door panels having their edges secured together and their body portions offset to form a chamber therebetween, of angle members disposed within said chamber having pairs of long and short branch members, the long branch members being secured to one end of said door panels at their outer ends and the short branch members being secured to said long branch members intermediate the ends thereof whereby to form a holder for a curtain rod.
7. In a metallic door structure, the combination with inner and outer sheet metal panels having their edges secured together and their body portions offset to form a chamber therebetween, of angle members located within said chamber, one of said angle members having branches of greater length than the other of said angle members whereby said first mentioned angle member may be attached to one of said sheet metal panels with the second mentioned angle member secured to said first mentioned angle member intermediate the ends thereof to form a holder spaced from said panels.
8. In a metallic door structure, in combination, inner and outer sheet metal door panels having their edges secured together and their body portions offset to form a chamber therebetween, a stamping disposed within said chamber provided with branches secured at the outer ends thereof to one of said panels, and a second stamping joining said branches intermediate their ends and cooperating with said first mentioned stamping to constitute a holder for a curtain rod.
9. In a curtain rod supporting structure, a plurality of stampings cooperating when assembled together to form a holder, a curtain rod socket seated in said holder, and cooperating means on said holder and said socket to prevent relative rotation therebetween.
10. In a curtain rod supporting structure, a holder, a curtain rod socket seated in said holder, and means in said holder and said socket adapted to be sprung into cooperative engagement whereby to prevent relative rotation between said holder and socket.
11. In a metallic door structure, the combination with inner and outer sheet metal panels having their edges secured together and their body portions offset to form a chamber therebetween, one of said panels having a flange at its upper edge to form the upper edge of the door, said flange having an opening therethrough, of a holder dis-

- posed within said chamber and a curtain rod socket insertable through said opening into said holder and means on said holder and socket adapted to be sprung into cooperative engagement with each other when said socket is inserted into said holder to prevent its removal therefrom.
12. In a metallic door structure, in combination with inner and outer sheet metal panels having their edges secured together and their body portions offset to form a chamber therebetween, one of said panels having a flange at its upper edge to form the upper edge of the door, said flange having an opening therethrough, of an expandable holder disposed within said chamber, and a curtain rod socket insertable through said opening and into said holder, said socket having means engageable by said expandable socket to prevent its withdrawal therefrom.
- 10

In testimony whereof, I affix my signature.

JOSEPH LEDWINKA.
